DESIGN FOR A SPACER BLOCK FOR A CAMERA

Ivar Benson and Harris W. Levy, Seattle, Wash.

Application February 25, 1941, Serial No. 99,488

Term of patent 7 years

To all whom it may concern:

Be it known that we, Ivar Benson and Harris W. Levy, citizens of the United States, residing at Seattle, in the county of King and State of Washington, have invented a new, original, and ornamental Design for a Spacer Block for a Camera, of which the following is a specification, reference being had to the accompanying drawing, forming part thereof.

Figure 1 is a side elevational view of the spacer block as it appears when attached to a camera, showing our new design, the opposite side of

which presents substantially the same appearance as the side shown.

Figures 2 and 3 are respectively an end elevational view and a perspective view of the spacer block only.

The essential features of our design reside in the spacer block shown in full lines.

We claim:

The ornamental design for a spacer block for a camera, substantially as shown and described.

IVAR BENSON.

HARRIS W. LEVY,
